US00D938724S

(12) **United States Design Patent** (10) **Patent No.:** **US D938,724 S**
(45) **Date of Patent:** **** Dec. 21, 2021**

(54) **RIDE-ON LUGGAGE**

(71) Applicant: **NINGBO PORT ZHONGDI
LUGGAGE MANUFACTURING
LIMITED**, Ningbo (CN)

(72) Inventor: **Weiliang Lin**, Ningbo (CN)

(73) Assignee: **NINGBO PORT ZHONGDI
LUGGAGE MANUFACTURING
LIMITED**, Ningbo (CN)

(**) Term: **15 Years**

(21) Appl. No.: **29/736,756**

(22) Filed: **Jun. 2, 2020**

(30) **Foreign Application Priority Data**

Mar. 13, 2020 (CN) 202030085077.X

(51) **LOC (13) Cl.** **03-01**

(52) **U.S. Cl.** **D3/279**
USPC **D3/279**

Assistant Examiner — Jessica M Gebhart

(57) **CLAIM**

The ornamental design for a ride-on luggage, as shown and described.

DESCRIPTION

FIG. 1 is a perspective view of a ride-on luggage showing my new design where the ride-on luggage is in a first configuration of use;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the ride-on luggage where the ride-on luggage is in a second configuration of use;

FIG. 10 is another perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines in the drawings illustrate portions of the ride-on luggage which form no part of the claimed design.

1 Claim, 16 Drawing Sheets
